Patented Dec. 10, 1918.

2 SHEETS—SHEET 2.

UNITED STATES PATENT OFFICE.

WILLIAM Y. DEAR, OF JERSEY CITY, NEW JERSEY.

DEVICE FOR RETAINING PRINTING-PLATES AND THE LIKE IN POSITION.

1,286,952.

Specification of Letters Patent. Patented Dec. 10, 1918.

Application filed July 30, 1915. Serial No. 42,706.

To all whom it may concern:

Be it known that I, WILLIAM Y. DEAR, a citizen of the United States, residing in the city of Jersey City, county of Hudson, and State of New Jersey, have invented certain new and useful Improvements in Devices for Retaining Printing-Plates and the like in Position, of which the following is a specification.

10 This invention relates to devices for holding printing frames, printing chases, and the like, in position upon a form-cylinder or other support, and more specifically to a retaining band or bands and rotatable adjusting means coacting directly therewith.

15 One of the objects of the invention is to provide an easily accessible device of the kind mentioned which shall permit a rapid positioning or removal of the plates from the cylinder. Another object is to provide a device which shall occupy a comparatively small space, so that the capacity of the support shall not be limited substantially, except by the size of the printing plates placed 20 thereon. Another object is to provide a device wherein a set of plates may be clamped or released simultaneously and which at the same time will permit the individual adjustment of the retaining member of each plate 25 of the set.

30 Other objects will be in part obvious and in part pointed out hereinafter.

35 My invention accordingly consists of printing plates or chases, retaining bands, and rotatable adjustable rolls operating directly to tighten and loosen the same.

40 In the accompanying drawings, wherein certain embodiments of my invention are shown and in which similar reference numerals designate similar parts throughout, Figure 1 represents a sectional elevation of a portion of a form-cylinder with the printing plate and retaining means thereon; Fig. 2 represents a plan view of a portion of the 45 cylinder and parts corresponding to the showing in Fig. 1; Fig. 3 represents a longitudinal sectional elevation taken on line III—III of Fig. 1; Fig. 4 represents a fragmentary longitudinal sectional elevation 50 taken on the line IV—IV of Fig. 1; Fig. 5 represents a modified construction showing a common means for simultaneously tightening and loosening a set of plates while permitting the individual adjustment of each; 55 and Fig. 6 is a section taken on line VI—VI of Fig. 5.

It is to be noted that while the drawings illustrate a complete retaining means for only one lot of plates, the number of sets that may be retained will be limited only by the superficial surface of the cylinder and the size of the plates.

Referring now more specifically to the showing in Figs. 1 to 4, 1 designates a form-cylinder which is provided with a plurality of sets of rectangular apertures, the apertures 2 of each set being laterally spaced from one another at equal distances and the apertures 3 of the adjacent set being circumferentially spaced at equal distances from the apertures 2. The apertures 2 and 3 are identical in shape and position upon the form-cylinder with the exception that they are as stated, circumferentially spaced from one another.

70 The printing frames 4 or similar means for holding a printing frame are held in position by retaining means extending between the corresponding apertures 2 and 3 in the two sets. These retaining means comprise flexible bands 5 and 6, preferably of steel or similar material fitted to assume the shape of and lie flat in channels in the surface of the printing plates when in position.

75 The band 5, being positioned adjacent the outer edge of the cylinder, is used to hold only the outer edge of the plate nearest this edge of the cylinder. The bands 6 are substantially double the width of this outer band and are adapted to contact with two plates adjacent their edges.

80 The means for holding the bands 5 and 6 in position upon the plates 4 is substantially identical, and a description of one will answer for all. One end of the band 5 is secured in position overlapping the aperture 2 by means of a plate 7 fitted to overlap its aperture 2 by about half the width of the aperture. Mounted on the outer end of this plate 7 is a second plate 8 to which is secured, slightly to one side of the center 85 thereof, the band 5.

90 The opposite end of the band 5 is secured to the periphery of the rotatable roll 9 which is positioned in the aperture 3, so that the band is maintained in substantially parallel relation with the sides of the cylinder. The roll 9 is held in position upon a shaft 10 which is in turn supported by a rectangular frame having substantially parallel radially disposed sides provided 100 with flanges 11 which seat in a shoulder in the walls of the aperture. Upon the hub 110

12 of the roller 9 is mounted a worm wheel 13 which is moved by a worm 14 passing through side bars 15 of the frame. The worm is provided with a squared head 16 to permit engagement by a wrench, the head projecting into the aperture 3, to one side of the band 5, and in such position that it is readily accessible within the aperture.

In operation the printing plates or similar devices are placed in position upon the form-cylinder with the channels 17 and 18 with which they are usually provided in position to receive the bands 5 and 6. When the plates have been adjusted, rotation of the head 16 of the worm will rotate the worm wheel and thereby the roll, whereby the band will be drawn tightly against the printing plates and will securely hold them in position. In order to prevent chafing and wear of the bands along the line of contact thereof with the edge of the aperture 3, a shoulder 19 is provided in the aperture, adjacent the line of contact, on which is fitted a seat 20 upon which is secured a beveled plate 21.

The terminals of the bands 5 and 6 and the plates 7 and 8 are attached by screws. These parts may thus be readily removed and replaced if desired. Plate 7, flanges 11 and 19, and support for the worm gear and roller construction are preferably integral, and removable from the cylinder as a unit.

It will be noted that in each of the apertures 2 and 3 there are positioned both the support of the overhanging end of the band 5 and also the worm gear and roller construction utilized to tighten the band. The worm gear and roller construction in each of the apertures 2 is adapted to tighten and loosen the bands 5 and 6 used for retaining a set of plates to the left in Figs. 1 and 2. In a similar manner the overhanging ends of bands 5 and 6 used with another set of plates succeeding the ones described, and to the right in Figs. 1 and 2 of the drawings, have fixed ends which overhang the apertures 3. By this arrangement it will be observed that a marked economy in space on the form-cylinder is attained and that in spite of the close proximity of the parts, the operation thereof is in no wise interfered with. The projection of the head of the worm to one side of the band which it operates and adjacent the mouth of the aperture in which it is seated enables an operator to engage the head with a wrench without difficulty, and by continuous motion of the wrench the band may be easily tightened or loosened, as may be desired. The whole of the apparatus is extremely simple in construction and consists of but a few parts, and it will be noted achieves among others the objects of the invention set forth above.

In Figs. 5 and 6 is shown a modified structure wherein is provided a device for simul-

taneously operating a set of plates. In using a set of plates, it will be understood that it becomes desirable to make a rapid attachment to the form-cylinder without making a separate adjustment each time. The modification here presented permits the simultaneous clamping of the individuals of the set of plates while permitting also the adjustment of a single plate if this be desired or necessary.

The construction employed to achieve the object above set forth comprises a worm gear and roller construction somewhat differently mounted in a series of apertures 22 similarly positioned to apertures 2 and 3 heretofore mentioned, but having a different shape; that is, the sides 23 of the apertures are circular. Each of the apertures 22 contains a worm gear and roller device and also a means for retaining the fixed end of the band 5. The worm gear and roller construction is supported by means of a common shaft 24, which is supported at its extremities by the arms 25 of the form-cylinder. This common shaft is turned by means of a worm wheel 26 operated by a worm 27, the worm and worm wheel being situated beyond the edge of the form-cylinder. The means of adjustment and support of this common shaft with respect to the rollers and the operating mechanism therefor is identical in each case, and a description of one will suffice for all. The frame for supporting each of the worm gear and roller constructions comprises an inwardly projecting arm 28 in which the hub 32 of the roller 33 is journaled and an arm 29 which is mounted rigidly on the shaft 24. The worm 30 is secured to an offset portion of the arm 29 and is in position to coact with the worm wheel 31 which is mounted upon the hub 32 of the roller 33. To this roller is secured the band 5 in the manner heretofore indicated.

According to this construction it will be noted that if the shaft 24 be revolved in one direction, it will, through the supporting arm 29, move the worm, which, being locked with respect to the worm wheel, will move the latter and thereby the roller. This action will take place in connection with each of the worm gear and roller constructions and therefore there will be, simultaneously, either a tightening or loosening of each of the bands 5 and 6, according to the direction in which the shaft 24 is turned. At the same time the individual tightening or loosening of any one of the bands may be accomplished by turning the head 34 of the worm, which will move its individual worm wheel and thereby the roller 33, without causing movement in any of the other parts. The curved sides of the apertures will permit the necessary swinging of the worm gear construction. The position of the parts

illustrated in Figs. 5 and 6 is that assumed prior to tightening the bands. Rotation of the worm 27 will cause a three-quarter revolution of the shaft 24, bringing the head of 5 the roller 34 into position in the opening 22 such that it may be readily engaged by a suitable wrench for its rotation when adjustment of an individual band is desired.

The construction set forth here also employs few parts and permits extremely rapid 10 adjustment of the plates upon the machine. It combines both strength and simplicity and may be used with facility by even an unskilled operative.

15 I realize that many apparently widely different embodiments of my invention may be made without departing from the spirit thereof, and I therefore do not desire to be limited to the specific embodiment set forth 20 except as indicated in the appended claims.

Having thus described my invention, I claim:

1. In combination, a plurality of printing frames, a form-cylinder acting as a support 25 therefor, an adjustable retaining device comprising rotatable rolls and circumferentially disposed bands, each of said bands having one end fixed and the opposite end secured for rotation to its respective roll, the fixed 30 end of one of said bands overhanging the rotatable end of the preceding band.

2. In combination, a printing frame, a form-cylinder therefor provided with circumferentially spaced apertures and an adjustable 35 retaining device comprising a band extending circumferentially from one of said apertures to the other, one end of said band being fixed and overhanging one of said apertures, and a rotatable roll seated in 40 the other of said apertures, the other end of said band being attached to said rotatable roll.

3. In combination, a printing frame, a form-cylinder having a series of laterally 45 and circumferentially spaced apertures situated along the edges of said frame, bands passing across the face of said frame from

one aperture to another, one end of each of said bands being fixed to overhang one of said apertures, and a worm gear and roller 50 construction situated in another of said apertures, the other end of said band being secured to said roller whereby upon rotation of said roller through said worm gear said band will be tightened circumferentially. 55

4. In combination, a printing frame, a form-cylinder provided with a plurality of sets of laterally spaced apertures, said sets being circumferentially spaced from one another, a plurality of bands extending substantially parallel to the sides of said form cylinder from the apertures constituting one set to the apertures constituting the next adjacent set, one end of each of said bands being fixed to overhang the apertures of one 60 set, and a worm gear and roller construction situated in the other set of apertures, the opposite ends of each of said bands being attached to its corresponding roller, the worm in said worm gear construction being 65 positioned so that its longitudinal axis is substantially parallel to the sides of the aperture and projecting to one side of the band, whereby upon rotation of said worm and roller construction the corresponding 70 band will be tightened across the face of said printing frame.

5. In combination, a plurality of printing frames, a form cylinder having laterally and circumferentially spaced apertures therein, 80 and retaining means for said frames comprising bands extending across the face of said frames, each having one end fixed to the cylinder, and a plurality of worm and worm wheel and roller devices seated in said 85 apertures and wholly below the surface of the cylinder, each of the worm wheels of said device being mounted on a common shaft and coacting with its worm to move said roller to tighten its respective band, 90 said worm wheel being capable of independent movement to provide an independent adjustment of its respective band.

WM. Y. DEAR.
